UNITED STATES PATENT OFFICE.

CHARLES LEFEBVRE, OF LOWELL, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM FOR LOOMS.

Application filed August 27, 1923. Serial No. 659,480.

To all whom it may concern:

Be it known that CHARLES LEFEBVRE, a citizen of the Republic of France, residing at Lowell, in the county of Middlesex and

5 State of Massachusetts, have invented a new and useful Weft-Detecting Mechanism for Looms, of which the following is a specification.

This invention relates to improvements in 10 weft detecting mechanism of the type shown in the prior patent to Ryon, No. 1,352,536, issued September 14, 1920. In this type of weft detecting mechanism the weft is simultaneously engaged by two detecting members, one of which is fixed to a supporting 15 slide and the other of which is pivoted thereon. The relative position of the two detecting members sometimes needs adjustment to suit different sizes of weft or other 20 changes in operating conditions.

It is the object of my present invention to provide an improved construction by 25 which the pivot or bearing of the movable detecting member may be very easily moved longitudinally of the supporting slide when ever such adjustment is found desirable.

My invention further relates to arrangements and combinations of parts which will be hereinafter described and more particularly pointed out in the appended claims.

A preferred form of my invention is shown in the drawings, in which—

Fig. 1 is a plan view of weft detecting mechanism embodying my improvements;

35 Fig. 2 is a plan view of certain parts of the detecting mechanism, with the upper plate of the supporting slide removed;

Figs. 3 and 4 are views similar to Fig. 2 but showing the parts in different positions;

40 Fig. 5 is a detail sectional elevation, taken along the line 5—5 in Fig. 1;

Fig. 6 is a transverse sectional elevation, taken along the line 6—6 in Fig. 2; and

45 Fig. 7 is a partial plan view of one end of the supporting slide.

Referring to the drawings, I have shown a weft detecting mechanism which is in

general of substantially the construction shown in the Ryon patent above noted and which includes a stand 10 adapted to be fixed to the loom frame and having a guideway or slide casing 11 formed at the end thereof. A supporting slide 12 is mounted in the guideway 11 and is yieldingly mov-

able forwardly (or to the left in Fig. 1) 55 against the tension of a compression spring 13.

A fixed detecting member 14 is secured to the rear or right hand end of the slide 12 and a movable detecting member 15 is 60 pivoted therein on a stud 16 and is normally positioned closely adjacent the detecting member 14. The pivoted member 15 has a laterally projecting arm 17 extending between the hooked end of a stop rod 65 18 and the rear end of a second rod 19. The rod 19 is mounted for endwise movement in suitable bearings within the slide or support 12 and the forward or left hand end of the rod 19 engages an arm 20 on a 70 rock shaft 21.

A second arm 22 on the shaft 21 is pivotally connected to a rod 23 slidable thereby into and out of the path of an actuating member 24. The actuating member is normally inoperative but when the rod 23 remains in its rearward position, in the path of movement of the member 24, the member 24 then becomes operative to indicate weft 75 exhaustion.

The stud 16 for the pivoted member 15 is not mounted directly on the slide 12 but extends through a slot 25 in the lower plate thereof (Fig. 5), being confined therein by a nut 26. The stud 16 also extends through 80 an opening 27 in a supporting rod 28 which is slidably mounted in the slide 12 and which is pressed yieldingly rearward by a spring 30.

The front portion of the support 28 is 85 formed as a round rod of reduced section upon which is threaded an adjusting nut 31 having a projection 32 adapted to engage the front end of the slide 12 and to act as a stop to limit rearward movement of the support 28 in the slide. The upper and lower plates of the slide 12 are provided with projecting portions 33 (Fig. 7) which enclose the end of the projection 32 and thus maintain the adjustment of the support 28. 95

The normal position of the parts is indicated in Fig. 1, with the movable detecting member 15 closely engaging the fixed detecting member 14. When the detecting mechanism engages a weft carrier W having a considerable amount of relatively soft weft or filling thereon, as indicated in Fig. 3, the 100 105

spring 30 permits the detecting member 15 to move bodily forward in the slide 12. Such movement further withdraws the rod 23 from the path of the actuator 24. When 5 the supply of weft becomes much reduced on the weft carrier W, as indicated in Fig. 2, the slide 12 will still be moved forward by engagement of the fixed detector 14 with the weft carrier W and the rod 23 will be sufficiently withdrawn to clear the actuator 24.

If, however, the weft becomes entirely exhausted upon the portion of the weft carrier W engaged by the detecting mechanism, the detecting member 15 will then be free 15 to turn upon its pivot 16, and the slight rearward movement of the slide 12 caused by engagement of the detector 14 with the weft carrier W will not be effective to move the rod 19 and arm 20 and withdraw the rod 23. The actuator 24 thereupon becomes operative to indicate a weft carrier transfer.

Whenever it is desired to change the relative longitudinal position of the detecting members 14 and 15, this change is very easily effected by pulling forward the support 28 and adjusting the nut 31 as may be necessary. This adjusting movement is a straight line movement longitudinally of the slide 12 and does not disturb the lateral relation 25 of the pivoted detecting member 15, the stop rod 18 and the rod 19.

Having thus described my invention and the advantages thereof, I do not wish to be limited to the details herein disclosed otherwise than as set forth in the claims but what 35 I claim is:—

1. A weft detecting mechanism for looms comprising a movably mounted slide, a detecting member fixed to said slide, a pivoted 40 detecting member, a movably mounted support on said slide for said pivotally mounted detecting member, and means to adjust said support in a straight line longitudinally of said slide, while maintaining a fixed trans- 45 verse position thereof.

2. A weft detecting mechanism for looms comprising a movably mounted slide, a detecting member fixed to said slide, a pivoted detecting member, a support for said pivot- 50 ed detecting member mounted for longitudi- nal movement in said slide, and means to

move said support yieldingly rearward in said slide.

3. A weft detecting mechanism for looms comprising a movably mounted slide, a detecting member fixed to said slide, a pivoted detecting member mounted adjacent thereto, a bearing for said pivoted detecting member, and means to adjust said bearing by a straight line movement longitudinally of 55 said slide, while maintaining a fixed trans- 60 verse position thereof.

4. A weft detecting mechanism for looms comprising a movably mounted slide, a detecting member fixed to said slide, a pivoted detecting member mounted adjacent thereto, a support for said pivoted detecting member mounted for yielding longitudinal movement 65 in said slide, and means to adjustably limit rearward movement of said support in 70 said slide.

5. A weft detecting mechanism for looms comprising a movably mounted slide, a detecting member fixed to said slide, a pivoted detecting member mounted adjacent thereto, a pivot stud for said pivoted detecting member, said stud extending loosely through 75 a longitudinal slot in said slide, and means to adjust said stud longitudinally in said slot.

6. A weft detecting mechanism for looms comprising a movably mounted slide, a detecting member fixed to said slide, a pivoted detecting member, a support for said pivot- 85 ed detecting member mounted for longitudi- nal movement in said slide and having a threaded front end portion, and an adjusting nut threaded on said end portion and engaging said slide.

7. A weft detecting mechanism for looms 90 comprising a movably mounted slide, a detecting member fixed to said slide, a pivoted detecting member, a support for said pivot- ed detecting member mounted for longitudi- nal movement in said slide and having a 95 threaded front end portion, an adjusting nut threaded on said end portion and engaging said slide, and means to hold said nut in adjusted position.

In testimony whereof I have hereunto 100 affixed my signature.

CHARLES LEFEBVRE.
